UNITED STATES PATENT OFFICE

HERBERT ABRAHAM, OF NEW YORK, N. Y., ASSIGNOR TO THE RUBEROID CO., OF NEW YORK, N. Y., A CORPORATION OF NEW JERSEY

SHINGLE

Application filed June 1, 1931. Serial No. 541,246.

This invention relates to shingles for covering the roofs and/or sides of buildings, and particularly to shingles made of asbestos-cement or the like.

5 The shingles are intended to be applied according to the Dutch-lap method in overlapping horizontal courses with one side and the upper edge of each shingle lapped and with the vertical joints of the several courses 10 broken.

An object of the invention is to provide shingles that can be laid with a side lap of different widths so that the vertical joints may be broken at different parts of the covering formed by the shingles.

Another object is to provide reversible shingles that may be laid with their sides lapping either from left to right or from right to left and with a side lap of different widths 20 in either direction.

A further object is to provide reversible shingles adapted to be laid with laps of two different widths and preperforated for the reception of fastening nails, the shingles being so arranged that when laid with laps of either width, the overlapping shingles will be supported in the immediate vicinity of their nailing perforations by portions of the overlapped shingles, thus permitting of driving 25 the fastening nails home without danger of breaking or fracturing the shingles.

A still further object is to provide the shingles with means for indicating the proper extent of head lap with which they are to be 30 laid.

The invention permits of applying the shingles from right to left or vice versa, and of forming a covering of two different appearances in either direction. One of the 35 advantages of the invention is that it provides a preperforated reversible shingle in which all of the perforations are used in laying the shingle, thereby avoiding the confusion and difficulties which arises with the 40 type of preperforated reversible shingle wherein only certain of the perforations are used in laying the shingle in either direction.

Other objects and advantages of the invention will be apparent to those skilled in the

art from the following description thereof, it being understood that modifications may be made therein, other than those described, within the scope of the invention.

The accompanying drawings illustrate a 55 preferred embodiment of the invention, in which:—

Figure 1 is a plan view of the shingle,

Fig. 2 is a plan view of four shingles assembled in overlapped relation with a side 60 lap of one width,

Fig. 3 is a plan view of two shingles laid with a wider side lap,

Fig. 4 is a similar view of two shingles laid in reversed position to a side lap in the 65 opposite direction,

Fig. 5 is a plan view of a shingle embodying a modified form of lap-gauge, and,

Figs. 6, 7 and 8 are plan views showing other modifications thereof.

70

1 indicates a shingle of rectangular form, preferably made of asbestos-cement, having perforations 2 and 2' adjacent two diagonally opposite corners, a perforation 3 in one lower corner, and an opening 4 in one upper corner. The perforations 2 and 2' are intended for the reception of nails for fastening the shingle to the roof or foundation, two nails being driven through each shingle and the perforations being so located that both the 75 nails will be covered by overlapping portions of other shingles. The perforation 3 is intended for the reception of an anchor or clincher for securing the exposed corner of the shingle to an underlying shingle. The 80 opening 4 provides a gauge for laying the shingle with a side lap of two different widths, as hereinafter described.

The shingle may be laid either with the opening 4 in the upper left hand corner, in 85 which case the shingles of each horizontal course will be side lapped in one direction as shown in Figs. 2 and 3, or the shingle may be turned 90° and laid with the opening 4 in the upper right hand corner, in which case the shingles will be side lapped in the opposite direction as in Fig. 4.

In the embodiment illustrated in Fig. 1, the lap-gauge opening 4 is in the form of a 90 square having vertical and horizontal diag-

100

nals. The length of these diagonals determines the extent of variation of width of the side lap in either position of the shingle. In applying the shingles from right to left, the perforation 2 of an overlapping shingle 5 is brought in to registration with one or the other of the horizontal corners 5 or 6 of the aperture 4 of an underlying shingle depending on the width of lap desired. For example, where it is desired to lay the shingle 10 with the lap shown in Figure 2, the perforation 2 of the overlapping shingle is brought into registration with the corner 5 of the lap-gauge 4 of the underlying shingle by inserting a nail through the perforation 2 and lap-gauge 4 and then bringing the nail shank against the corner 5, whereupon the shingles are fastened by driving the nail home. If a wider lap is desired, the perforation 2 is registered with the opposite corner 20 6 of the lap-gauge, as in Fig. 3, and the shingles are then nailed. Similarly, when the shingles are applied from left to right, the perforation 2' of the overlapping shingle is registered with either the corner 5' or 6' 25 of the lap-gauge of the underlying shingle. This is indicated in Fig. 4 where two shingles, applied from left to right, are shown as laid with a wide side lap.

30 The form of the lap gauge is subject to various modifications. One modification is shown in Fig. 5 where the lap-gauge is in the form of a cross, the opposite ends 5 and 6, or 5' and 6', being used to determine the desired width of lap when the shingles are applied in either direction. Another modification is shown in Fig. 6 in which the lap-gauge is in the form of a triangle. With a gauge of this form, the corners or angles 35 5 and 6 are used to indicate the two different widths of lap when the shingles are laid in one direction, while the corners 5' and 6 are used when the shingles are laid in the opposite direction. Fig. 7 shows a lap-gauge in 40 the form of a circle whose diameter is such as to define the limits of variation in width of the lap when the shingles are laid in either direction. In the form shown in Fig. 8 the lap-gauge 4 instead of consisting of a single 45 aperture comprises three correlated openings 5, 5', and 6. With this form of gauge, when the shingles are applied from right to left, the openings 5 and 6 are used to indicate the two different widths of lap, while when the 50 shingles are applied from in the opposite direction, the openings 5' and 6 are used for that purpose.

If desired, the shingle may be notched in 55 two adjacent edges, as at 7—7' to indicate the proper extent of head lap with which the shingle is to be laid. Referring to Fig. 2, it will be seen that shingles of the upper course are laid with their lower edges registering with the notches 7 of the shingles of 60 the lower course, thus determining the length

of the head lap. When the shingles are laid in reversed position, the notches 7' serve to indicate the extent of head lap. It will be further noted that the perforation 2' is so located that the shank of a nail driven 70 through said perforation will just clear the upper edge of the shingles of the lower course.

The exposed overlapping lower corner of each shingle of a course is secured as usual to an underlying shingle of the same course 75 by means of a suitable anchor or clincher 8 having a portion which is bent down over said corner.

It will be seen from the foregoing description that the shingles may be applied from 80 right to left or from left to right, as desired, and to have a side lap of different widths in either direction of application. This variable side lap permits of forming a covering in which the vertical joints may be broken 85 at different parts. For example, with shingles of the particular proportions of those herein illustrated, when laid with the shorter lap the shingles will break joint in thirds, and when laid with the longer lap they will 90 break joint in halves, in each case forming a covering of different appearance.

What I claim is:—

1. A shingle adapted to be laid with a side 95 lap of different widths, said shingle being substantially rectangular in form, and having a gauge in one upper corner for indicating the different widths of laps with which the shingle may be laid and a perforation in the opposite upper corner for the reception 100 of a fastening nail, the particular width of lap with which the shingle is to be laid being determined by bringing the nailing perforation of an overlapping shingle into position with that part of the lap-gauge of an 105 overlapped shingle that indicates a lap of the desired width, said shingle being so arranged that the overlapping shingle is supported in the immediate vicinity of its nailing perforation by a portion of the overlapped shingle. 110

2. A shingle adapted to be laid with a side 115 lap of different widths, said shingle being substantially rectangular in form, and having an aperture in one upper corner providing a gauge for indicating the different widths of laps with which the shingle may be laid and a perforation in the opposite upper corner for the reception of a fastening nail, the particular width of lap with which the shingle is to be laid being determined 120 by bringing the nailing perforation of an overlapping shingle into position with that part of the lap-gauge aperture of an overlapped shingle that indicates a lap of the desired width, said shingle being so arranged 125 that the overlapping shingle is supported in the immediate vicinity of its nailing perforation by a portion of the overlapped shingle.

3. A reversible shingle of rectangular form adapted to be laid in side lapped rela- 130

- tion in either of two directions with laps of different widths, said shingle having a gauge in one of its upper corners for indicating differences in width of the side lap, and having
- 5 a perforation in the other upper corner and a second perforation in the diagonally opposite lower corner, both of said perforations being adapted to receive fastening nails and being symmetrically disposed in relation to the lap-gauge, the width of the side lap being determined by registering the upper nailing perforation of an overlapping shingle with a particular portion of the lap-gauge of an overlapped shingle.
- 10 4. A reversible shingle of rectangular form adapted to be laid in overlapped relation in either of two directions with a side lap of different widths and a fixed head lap, said shingle having an aperture in one of its upper corners providing a gauge for indicating differences in width of the side lap, and having a perforation in the other upper corner and a second perforation in the diagonally opposite lower corner, both of said perforations being
- 15 adapted to receive nails and being symmetrically disposed in relation to the lap-gauge aperture, and notches in two adjacent sides of the shingle, the upper one of said notches serving to define the extent of the head lap,
- 20 the width of the side lap being determined by registering the upper perforation of an overlapping shingle with a particular portion of the lap-gauge aperture of an overlapped shingle.
- 25 5. A covering comprising shingles of substantially rectangular form laid in overlapping horizontal courses with both a side lap and a head lap and with only one lower corner of each shingle exposed, each shingle having two perforations for the reception of nails, one of said perforations being disposed in one upper corner and the other being disposed in the diagonally opposite lower corner, a lap-gauge in the opposite upper corner
- 30 for indicating the extent of the side lap, the upper perforation of each side-lapping shingle of a course being registered with a particular part of the lap-gauge of the adjacent side-lapped shingle of the same course, said
- 35 shingles being fastened by nails driven through both perforations, the lower exposed corner of each shingle having a perforation for the reception of a storm anchor for securing it to an underlying shingle.
- 40 55 Signed at New York city, in the county of New York and State of New York, this 26th day of May, A. D. 1981.

HERBERT ABRAHAM.
